UNITED STATES PATENT OFFICE.

CHARLES ALGERNON PARSONS AND ALFRED QUINTIN CARNEGIE, OF NEWCASTLE-UPON-TYNE, AND STANLEY SMITH COOK, OF WALLSEND, ENGLAND; SAID CARNEGIE AND SAID COOK ASSIGNORS TO SAID PARSONS.

CONSTRUCTION OF TURBINE AND LIKE ROTORS.

1,210,978.

Specification of Letters Patent.

Patented Jan. 2, 1917.

Original application filed October 9, 1913, Serial No. 794,353. Divided and this application filed March 20, 1916. Serial No. 85,510.

To all whom it may concern:

Be it known that we, CHARLES ALGERNON PARSONS, K. C. B., a subject of the King of Great Britain and Ireland, and residing at 5 Heaton Works, Newcastle-upon-Tyne, in the county of Northumberland, England, ALFRED QUINTIN CARNEGIE, a subject of the King of Great Britain and Ireland, and residing at Heaton Works, Newcastle-upon- 10 Tyne, in the county of Northumberland, England, and STANLEY SMITH Cook, a subject of the King of Great Britain and Ireland, and residing at Turbinia Works, Wallsend-on-Tyne, in the county of North- 15 umberland, England, have invented a certain new and useful Improved Construction of Turbine and Like Rotors, of which the following is a specification.

This invention relates to the construction 20 of rotors for turbines and the like such as are described in application Serial No. 794,353, filed October 9th, 1913, of which this application is a division.

Referring to the accompanying drawings:—Figure 1 shows a form of the present invention in which cup-like members spigoted together are employed to form a rotor suitable for a turbine. Fig. 2 shows an application of the present invention to 30 a gear wheel rotor of the double helical type. Fig. 3 shows an alternative construction to Fig. 2. Fig. 4 illustrates alternative hub forms. Fig. 5 shows a modified form of rotor similar to that shown in Fig. 2. Fig. 6 illustrates the application of the 35 present invention to large gear wheel rotors.

In carrying the invention into effect according to one form, see Fig. 1, the members *a*, which form part of the cylindrical 40 surface, *b*, of the rotor are cup-shaped, and essentially short cylindrical drums having one end thereof open and the other closed or partially closed by an inwardly projecting flange, *c*, which in some cases may 45 extend to the shaft.

The flanges *c* are preferably of strength sufficient to support the entire circumferential portion of the drum independently of its circumferential strength so that, for 50 example, in the case of a fault in the circumferential portion of any one cup the structure will still be strong enough to withstand all stresses to which it is sub-

jected. The flanges may be reinforced at the center if desired. The members thus 55 formed are attached to one another and to the shaft, the rims being spigoted into one another, as at *d*, or otherwise suitably connected, for example, by a short flange formed on the rim at the open end thereof. 60

Distance pieces, *e*, forming hubs of any suitable shape may be inserted between the flanges *c* resting upon the rotor shaft, *f*, and may be riveted or otherwise attached to the flanges against which they abut. 65

In the case of a stepped rotor the rim of one member is spigoted into or otherwise suitably attached to the closed end of the adjacent member. Usually such members are made by pressing rolled plates into the 70 required shape.

The attachment of the drum to the rotor shaft for the purpose of transmitting torque may be effected by suitable means such as a key *g* at one or both ends of the drum 75 or along the whole or a considerable part of its length.

In constructing a double helical gear wheel, for example, see Fig. 2, two members, *a*, of the cylindrical type above described 80 with reference to Fig. 1, are threaded on a shaft, *f*, with their closed ends, *c*, back to back, connected by bolts, *h* and separated, if necessary, by suitable distance pieces *j*. The members are preferably riveted or bolted 85 to a suitable cast iron or cast steel hub, *k*, secured to the shaft, the helical teeth being cut on the periphery, *b*, of the disks either before or after assemblage, the teeth may be cut upon a ring *l* shrunk upon the outer periphery of *a*, *a*, see Fig. 3. If desired, the rims of such wheels may be stiffened by angles, *m*, attached near the open end of each member, or such ends may be closed by complete disks securely attached to the rim or to 90 the shaft, or to both.

Alternative hub constructions are illustrated in Fig. 4. In all constructions of hub, serrations may be formed upon the portions *c*, of the members, *a*, and upon the members 100 forming the hub, and as shown in Fig. 4 these serrations may be held close together by means of nuts *p*, screwed upon screwed portions of the hub *k*, which pass through holes in the flanges *c*. It is convenient to 105 mount the hubs, *k*, of the gear wheels upon

cone portions of the rotor shaft, nuts *n*, being employed to secure the hub upon the cone. Keys or the like are provided for the purpose of transmitting torque from the gear wheel to the shaft, or vice versa.

Fig. 5 shows a modified form of gear rotor construction in which one cup-shaped member *a*, is employed connected by its flange, *c*, to the hub. The flange, *c*, of the other cup-shaped member is not continued to the hub, but sufficient of the flange is provided to permit of bolting or riveting to the other member. Right and left hand or single hand helical teeth may then be cut upon the periphery, *b*, of the rotor.

In the case of large gear wheels, as shown in Fig. 6, two members of the cylindrical cup type are assembled on the shaft with their closed ends, *c*, separated by a distance piece, *e*, forming a hub, while the parts having the cylindrical surface, *b*, are connected together or spigoted into one-another, as shown at *d*, and the whole structure is held in position in any suitable manner, as by a nut *n* and a collar *o*. As before, right or left hand helical teeth may then be formed on the rotor, and two such elements separated where necessary by a suitable distance piece may be combined to form a complete gear wheel.

Many further modifications, it will be seen, may be made in the manner of carrying the invention into effect without in any way departing from the spirit of the same.

Having now described our invention, what we claim as new and desire to secure by Letters Patent is:—

1. A rotor comprising in combination a plurality of cup shaped elements, hub portions between said elements, and means connecting said hub portions and said elements.

2. A rotor comprising a pair of cup shaped elements, hub portions between said elements, distance pieces between said elements, and means connecting said hubs and said elements and said distance pieces and said elements.

3. In a rotor comprising cup shaped elements and hub elements, means for connecting said cup shaped elements and said hub elements comprising screwed portions upon said hubs entering holes in said cup shaped elements, and nuts upon said screwed portions to clamp said cup shaped elements.

4. A rotor comprising a pair of cup shaped elements, hub portions between said elements, distance pieces between said elements, and means connecting said hubs and said elements and said distance pieces and said elements, and a toothed ring secured upon the outer peripheries of said elements.

In testimony whereof we have affixed our signatures.

CHARLES ALGERNON PARSONS.
ALFRED QUINTIN CARNEGIE.
STANLEY SMITH COOK.
